UNITED STATES PATENT OFFICE.

ROBERT D. CODY, OF DETROIT, MICHIGAN, ASSIGNOR TO SAMUEL STEIN, OF NEW YORK, N. Y.

MULTIPLE-BURNER INCANDESCENT LAMP.

1,032,325.

Specification of Letters Patent.

Patented July 9, 1912.

Application filed January 15, 1912. Serial No. 671,322.

To all whom it may concern:

Be it known that I, ROBERT D. CODY, a citizen of the United States, residing at the city of Detroit, in the county of Wayne and State of Michigan, have invented a new and useful Improvement in Multiple-Burner Incandescent Lamps, of which the following is a specification.

My invention relates to incandescent gas lamps of the type using inverted burners with incandescent mantles.

The objects thereof are to provide a new and improved regulating valve by which the flow of gas to the burners is controlled and from which at the same time supplemental gas may be supplied to a pilot light having an independent gas supply whereby the latter may be made to flash just before the main current of gas is turned on to the principal burner, and also to make a similar flash after the gas is turned off from said burners. I also provide a new and improved head by which a quick supply of gas to the mantles may be had, thereby reducing the tendency to make explosive mixtures and cause the flame to flash back. A screen is also provided as a further protection against "flash back," the same being located outside of the body of the lamp and readily accessible for cleaning or change; and I provide a special mechanism whereby a single chain may be used to operate the device for turning the gas on and off from the principal burner.

The principles of my invention are illustrated in the drawings, in which—

Figure 1 represents a vertical section of a lamp of the character described provided with my improvements; Fig. 2 shows a single chain pull with counter-weights for operating the principal valve; Fig. 3 is a section of Fig. 2 on the line 3—3; Fig. 4 is an enlarged section of Fig. 3 on the line 4—4, showing the controlling valve closed; Fig. 5 is a similar view showing the controlling valve partly turned; Fig. 6 is a section of Fig. 1 on the line 6—6; Fig. 7 is a view of the screen with its mounting frame taken on the line 7—7 of Fig. 3; Fig. 8 is a cross section of Fig. 1 on the line 8—8; Fig. 9 is a cross section of Fig. 1 on the line 9—9.

Further describing my invention with reference to the drawings, in which like characters of reference denote like parts

throughout: 1 is the body portion, and 2 the globe attached thereto, of a lamp of the character indicated above. The principal feed pipe 2' extends downward into a union 3. To the lower part of the union is attached a burner head 4, the outer walls of which represent in cross section a truncated cone. Within the same and having its walls substantially parallel with the outer walls is a cone-shaped portion 5, the lower edges 65 of which are substantially flush with the lower edges of 4 and together with the same are attached to an annular member 9 in which at regular intervals are secured the burner tubes 10—10—10, which convey gas 70 to the mantles 11.

The union 3 is divided by partition 12, thereby forming the upper chamber 13 and the lower chamber 14. From the side of the union 3 at chamber 13 is led a horizontal pipe 15 which enters the valve casing 16 substantially in a line with its central longitudinal axis. An off-set 18 extends from the valve casing and has a perforation 19 extending into the same to a point 20 at which is attached a small pipe 21 terminating in the pilot burner 22. The flow of gas from the supply through pipe 15 is continuous and uninterrupted except as regulated by the screw 23. The conical valve plug 25 is seated in the casing 16. A stem 26 is extended outwardly and passes through a gland 27, having a central recess containing a spiral spring 28. The said spring presses upon the shoulder 29 of the valve plug 25, thereby holding the same firmly in its seat under adjustable pressure of the spring, which may be tightened or loosened by screwing the gland inwardly or outwardly. A collar 30 is secured on the stem 26, and, spaced therefrom by a narrowed neck on said collar, is a ratchet 31 having four teeth 32 placed at equal distances around its periphery. Between the enlarged portion of said collar and the ratchet disk and upon the neck of said collar is loosely mounted a lever 33 having a chain 34 attached to one end and a counter-weight 35 attached to the other end. A gravity actuated dog 36 is pivoted at 37 to said lever and is adapted to engage successively the peripheral teeth on the ratchet disk 31, such engagement taking place normally in the position shown in Fig. 2. The lever moves through an arc slightly greater than the fourth of a circle and with 110

each downward pull of chain 34 the ratchet and the valve plug 25 attached thereto are moved through an arc of 90 degrees to a fixed position. An indicating hand 38 attached to the valve stem is so related to the apertures therein that when horizontally placed the main current of gas is cut off while when in vertical position the flow of gas is established.

10. As above stated the conical valve plug 25 has an axial bore as shown at 40. It also has a transverse opening 41 through the peripheral walls so that when positioned as shown in Fig. 4 the current of gas through 15 passes longitudinally of the plug downwardly through the tube 42 and then through the pipe 43 until it reaches the air intake governed by the damper 44 and thence to the mixing tube 45, from which 20 it passes through the chamber 14 to the distributing head 5'. The floor of said head having a conical upward projection as hereinbefore described causes the volume of gas to be distributed quickly to the burner pipes 25 10 instead of being checked or "buckened" by a chamber having a flat base, one much longer than that therein used as is the usual practice.

When the gas leaves the shut-off valve and 30 casing 16, it passes through the connection 46 into the chamber 47 through which passes the stem 48 of needle valve 49, by which the immediate flow of gas to the burners is regulated. But the screw 44' is 35 designed to check this flow, thus allowing the gas to obtain a regular and full expansion before it is released through the needle valve to the mixing tube. Undue pressure of gas is thus prevented and blowing, whistling and other like noises are entirely avoided.

Transversely of the mixing tube is a casing 50 adapted to receive a removable slide 51 in which is placed a flat screen 52 45 through which the gas passes on its way to the burners. The screen being outside the lamp is not subjected to the heat thereof and it is not subject to carbonization or deterioration thereby. When for any reason it is 50 desirable to change the screen the slide is readily accessible, and when removed from the guideways the screen can readily be replaced, even when the lamp is heated. There is a constant minimum flow of gas 55 from the principal source of gas supply from the pilot light through the aperture 19 as above. My apparatus is arranged to increase such flow so as to produce a "flash" at the time the gas is turned on to the principal burners, thereby igniting the same before an explosive mixture is created, and also to check the increased flow as soon as 60

ignition takes place. The pilot burner frequently becomes carbonized while the principal light is burning. I have found that 65 this carbon may be removed by a second "flash" at the time the principal burner is extinguished. Both the initial and final flash may be produced by arranging the auxiliary ports 55 in the valve plug 25 in 70 proper relation to the opening 40 in said plug. The increased volume of gas will then flow to the pilot burner through the conduits 56 and 57.

I claim:

1. In an incandescent lamp; the combination with a burner head comprising a conical outer wall, an annular member secured to the lower part of said wall, and a conical inner wall attached to said annular member 80 and extended upwardly within said outer wall, of a supply pipe attached to the apex of said outer wall and centrally aligned with the axis of said inner wall.
2. In an incandescent lamp having a principal source of gas supply and a pilot burner connected therewith; the combination of a principal burner, a conical valve casing having peripheral outlet openings adapted to communicate with the principal burner and 90 the pilot burner, a conical valve plug having an axial inlet opening, a plurality of diametrically opposed principal outlet openings adapted to register with the casing openings communicating with the principal burner, and a plurality of outlet openings so related to the principal openings as to register with the pilot light outlet openings immediately before the principal openings in the casing and plug are connected 95 and immediately after said openings are disconnected, and means for giving said plug successive half revolutions.

3. In an incandescent lamp, the combination of a body portion having burners therein, a mixing tube extended outside said body portion, and a screen placed transversely of said mixing tube externally of the body of said lamp.

4. In an incandescent lamp, the combination of a body portion having burners therein, a mixing tube extended outside said body portion and provided with a transverse guideway external to the body of the lamp, and a screen removably mounted in said 110 guideway.

In witness whereof, I have hereunto subscribed my name, this 6th day of January A. D. 1912, in the presence of two subscribing witnesses.

ROBERT D. CODY.
